Edward C. Osgood INVENTOR.

Patented June 5, 1928.

UNITED STATES PATENT OFFICE.

EDWARD C. OSGOOD, OF ABERDEEN, MARYLAND.

DEVICE FOR CLEANING WELLS.

Application filed April 26, 1924. Serial No. 709,104.

Practically all wells of the, so called, open type collect sediment which tends to contaminate the water and for sanitary and other reasons should be periodically removed.

5 Heretofore this operation has usually been accomplished by one person descending into the well and with scoop or shovel dipping the sediment into a bucket to be raised to the ground surface by a second person.

10 This is a difficult and very dangerous operation due to the cramped position of the person in the well and to the chance of injury from poisonous gases, crumbling walls, falling buckets and so forth.

15 By the use of my invention wells may be cleaned of sediment quickly, efficiently and with entire safety, by one person, the work being done from the well platform or ground surface.

20 My invention relates to that type of dredging device in which are used hinged jaws or scoops so formed as to constitute practically a bowl or "bucket" when closed together around a central, normally vertical, 25 axis and constructed to open outward from the bottom, and provided with means for closing them while in contact with material to be removed.

I am aware that dredging devices, commonly called "buckets" answering the above general description and having two, three or four jaws or scoops have been successfully used for many years. My claims, therefore, are for improvements adapting this type of dredger to the purpose of cleaning wells by removing sediment therefrom.

Dredging devices of the bucket type hitherto in use have been somewhat unsuited for use in cleaning wells due to the fact that 40 the outrush of water from between the scoops during the act of closing same, and, also, the currents caused by raising the filled bucket to the surface of the water, act to wash out of the bucket the lighter particles 45 of sediment which, due to their usually vegetable nature, are most important to remove.

The construction and action of my device is such as to effectually retain these lighter particles within the bucket as is clearly shown in the following specifications and accompanying drawings.

In accompanying (two) drawings Figure 1 is a plan view showing the appearance 55 of the device when closed; Figure 2 is a projection of Fig. 1 in vertical section

through the axis—(shaft 11 not in section). To avoid confusion, only one of the actuating arms 4 is shown in this figure. Figure 3 is a plan showing the device in open position and with upper part of cylinder 1 cut away and piston 7 removed to show the position of actuating arms 4, 4, 4, relative to each other and to the spreader 12. Figure 4 is a projection of Fig. 3 in elevation and partly in section showing the device in open position, also showing the method of locking it in that position by means of spreader 12.

In all the figures like numerals refer to 70 like parts.

Following is a description in detail of the construction and operation of the device.

To a central, normally upright, cylinder 1 are so hinged, by lugs 16 and pivot screws 75 17 the scoops 2—2—2 that they may swing to and from the axis of the cylinder 1 in planes of said axis and so shaped that, when swung together, meeting at the axis, they constitute a bowl or bucket suitable for holding 80 sediment substantially as shown in Figs. 1 and 2. At the upper edges of these scoops, and constructed to swing clear of the lower edge of cylinder 1, are axisward projecting flaps 3, preferably integral with said scoops, 85 of such form as to meet at their edges when in closed position to constitute a cover to said bowl.

Rigidly attached to each scoop 2 is an actuating arm 4 so formed and placed as to 90 approach and pass the axis of cylinder 1, terminating within said cylinder and pivotally attached at its end to links 5—5.

Vertically movable within cylinder 1 but 95 kept from turning therein by V-shaped ribs 19 engaging corresponding grooves in its edge is a piston 7 having lugs 6 pivotally joined to links 5.

Rigidly attached to the piston 7 is the hollow piston rod 8 extending upward 100 through guide sleeve 9 and terminating in suitable means, as ring 18, for attaching a rope. Guide sleeve 9 is supported by braces 10, both sleeve and braces being preferably integral with the cylinder.

105 A hand hold 15 is attached to one of the braces as shown.

Fitting loosely within piston rod 8 is the shaft 11, also, preferably, hollow; this shaft extends well within, and is guided by, piston rod 8 and also extends below it, terminating 110 in the foot plate 13 and bearing, rigidly at

tached, the spreader 12. This spreader 12 is held in relative rotary position and also limited as to its relative vertical motion by the stud 14 fast to spreader 12 but having a limited, free vertical motion in piston 7.

In operation.—Upon lifting the device by hand hold 15 the weight of parts within the cylinder causes scoops 2—2—2 to swing outward into open position as shown in Figs. 3 and 4. The downward movement of the piston 7 permits a like movement of foot-plate 13 and spreader 12, the latter engaging with the beveled bases of actuating arms 4—4—4 as shown in Fig. 4. This engagement locks the device in open position so that it may be lowered, open, into the well by a rope or other means attached to ring 18.

Upon coming in contact with the bottom of the well the foot plate 13 with attached spreader 12 is pushed, relatively, upward thus releasing the spreader 12 from engagement with the arms 4—4—4.

A subsequent upward pull on the rope will raise the piston 7 within the cylinder 1 causing a suction from below and, simultaneously, by means of the links 5 and the actuating arms 4, will cause the scoops 2—2—2 to swing axisward gathering any loose material in their way. When closed, the scoops 2—2—2 with their flaps 3—3—3 constitute, in effect, a covered bowl efficient to protect its contents from loss by washing.

What I claim is:—

1. Multiple scoops hinged to a supporting frame to swing together centrally or open outwardly, rigidly attached actuating levers extending inwardly and so placed and shaped that, when the scoops are opened widely, each lever will extend under one and over another of the corresponding levers, the purpose being to gain greater length of levers without interference.

2. A tubular frame of uniform cross sec-

tion, preferably a hollow cylinder, of normally vertical axis, open at the ends for the free ingress and egress of water, scoops hinged thereto to swing to and from the downwardly extended axis of said tube in planes of its axis, a piston movable within, and in line of the axis of, said tube, and means connecting said scoops with said piston so that upward lineal movement of the piston will cause axis-ward swinging movement of the scoops and, simultaneously, create an upward suction within the embrace of the scoops.

3. The combination of a scooping element having multiple scoops with a suction element, the latter acting to withdraw the water from between the scoops while the scoops are closing.

4. In a well cleaning device having scoops so hinged to a common frame as to swing radially below the frame, a central vertical shaft, independently movable vertically, extending below said frame and terminating in a foot plate, and having, rigidly attached, a spreader with radial arms fitted to engage with interior projections below the hinges on said scoops so as to hold the scoops in open position and to release them by relative upward movement of the spreader.

5. Multiple scoops, hinged to close toward and open from a common axis and in planes thereof, means for automatically locking same in open position and releasing same by contact with bottom of well, said means consisting of a vertical, independently movable shaft having rigidly attached a spreader constructed to engage said scoops when in open position and releasable by a slight relative upward movement and a foot-plate attached to the lower end of said shaft for imparting such movement by contact with bottom of well, substantially as shown.

EDWARD C. OSGOOD.
